UNITED STATES PATENT OFFICE.

CHARLES ALBRECHT, JR., OF SCHLEISINGERVILLE, WISCONSIN.

DOOR-OPERATING MECHANISM.

1,257,172.

Specification of Letters Patent. Patented Feb. 19, 1918.

Application filed July 18, 1917. Serial No. 181,388.

To all whom it may concern:

Be it known that I, CHARLES ALBRECHT, Jr., a citizen of the United States, residing at Schleisingerville, in the county of Washington and State of Wisconsin, have invented new and useful Improvements in Door-Operating Mechanism, of which the following is a specification.

My invention relates to door operating mechanism and has for its primary object to provide a door operating mechanism which is adapted to be actuated to open the door upon the depression of a platform located in the roadway adjacent the door.

15 A further object of my invention is to provide a door opening mechanism, the initial operation of which serves to retract the latches of the door.

With these and other objects in view which will be hereinafter fully described and particularly pointed out in the claims, the invention consists in the novel construction and arrangement of parts illustrated in the accompanying drawings forming a part of 25 this specification, in which:—

Figure 1 is a top plan view of a door operating mechanism embodying my invention.

Fig. 2 is a vertical section in side elevation of the same,

30 Fig. 3 is an enlarged top plan view of the pinion and segment mechanism of the latch carrying the door,

Fig. 4 is an enlarged front elevation of the same.

35 Like characters of reference indicate like parts in the various views.

In the drawings 1 designates a door frame upon the respective sides of which a pair of doors 2 and 3 are mounted for swinging movement by means of hinges 4. The door 3 is equipped with spring latches 5 at the upper and lower ends thereof which engage the lintel and the threshold of the door frame respectively to lock the same in closed 45 position against the jamb 6 of the door frame. The door 3 is provided with an overlapping strip 7 which extends over the adjacent edge of the door 2, when the doors are closed, and serves to hold the door 2 against the jamb 6. A cable 8 is provided for each door and one end of each cable 8 is secured to its respective door near the free end thereof, the length of each cable being trained over a respective pulley 9 mounted upon the 55 lintel of the door. The cables are then trained over respective pulleys 10 mounted

on respective sides of the door, and have weights 11 secured to their other ends which serve to normally retain the doors in closed position.

60 Mounted on each door near its upper end thereof is a bracket 12 upon which is mounted a pinion 13 disposed in axial alinement with respective hinges 4. A second bracket 14 is mounted upon each side member of the door frame 1 adjacent the respective bracket 12 and a segment gear 15 is pivotally mounted thereon and adapted to mesh with the respective pinion 13, each segment having an arm 16 extending laterally therefrom.

65 A longitudinal recess 17 is formed in the roadway leading through the door and extending on either side thereof, said recess being disposed in the path of the wheels of a vehicle passing through said door. A rock 70 shaft 18 extends across the roadway just below the door and is mounted for pivotal movement in bearings 19 mounted on the threshold of the door frame. Said rock shaft has a crank 20 formed thereon and lying in the recess 17, for purposes hereinafter described, and has arms 21 extending upwardly at either end thereof just in front of the respective side members of the door 1. The brackets 14 have arms 22 formed thereon and extending outwardly in front of the respective arms 16 of the segment gears 15, pulleys 23 being mounted upon the outer ends of the respective arms 22 upon horizontal axes. Cables 24 are trained over respective pulleys 23 and have their upper ends secured to the free end of respective arms 16 of segment gears 15. The lower portions of said cables 24 are trained over respective pulleys 25 and have their lower ends connected to respective hooks 26, said hooks engaging the holes in the ends of respective arms 21 of the rock shaft 18. It will be noted at this point that when the rock shaft 18 is pivoted to move the arms 21 thereof 75 away from respective side members of the door frame the cables 24 pull the arms 16 of the segment gears 15 outwardly, and the segment gears move the pinions 13 to open the doors 2 and 3.

80 85 90 95 100 105 110
Mounted within the recess 17 at either end thereof is a vertical standard 27, and cams 28 are mounted thereon for vertical sliding movement by means of pairs of studs 29, secured to respective cams engaging respective vertical slots 30 of the standards. A lateral projection is formed on each standard 27 and

have studs 32 extending upwardly therefrom. A coiled compression spring 33 encircles each stud and abuts the respective projection 31 with its lower end and an 5 overlying portion of the respective cam 28 whereby each cam is normally retained in its upper position. A platform 34 is mounted for vertical movement in the recess 17 and has its respective ends secured to the 10 cams 28, the upper surface of said platform lying slightly above the surface of the roadway when said cams are in normal position. A plate 35 is hinged to either end of the platform 34 and have the free ends thereof 15 resting upon the roadway whereby a vehicle wheel will easily roll upon the platform 34. A lever 36 has its lower end pivotally mounted upon the respective standard 27 and has a cam surface 37 formed thereon which is 20 adapted to be engaged by the respective cam 28, and the upper end of each lever 36 is pivotally connected to the end of a connecting rod 38, the opposite end of each connecting rod being pivotally mounted upon 25 the crank 20 of the rock shaft. When a vehicle wheel rolls upon the platform 34, the weight thereof depresses the platform 34 and the adjacent cam 28, the movement of the cam being transmitted to the respective lever 36 through the cam surface 37 thereof, and the rock shaft 18 is operated through the medium of the respective connecting rod 38 to open the doors, as hereinbefore described. It will be noted at this 35 point that as the vehicle wheel moves along the platform 34 and reaches the center thereof both cams are depressed, and as the wheel moves toward the farther end the cam which was first depressed rises, the other cam being now depressed holding the door open as before. When the vehicle wheel passes off of the platform both cams return to normal position and the doors are allowed to close under the influence of the weights 11.

40 The segment gear 15 of the door 3 has an upwardly facing cam 39 formed thereon, and the bracket 12 of said door 3 has an arm 40 extending outwardly therefrom upon which is pivotally mounted a lever 41, the 45 outer end of which is adapted to be engaged by said cam 39. Cables 42 are connected to respective latches 5 and are trained over pulleys 43 mounted upon the door 3, the other ends of said cable being connected to 50 the other arm of the lever 41. The cam 39 is so disposed upon the segment gear 15 that upon the initial opening movement of said segment gear the lever 41 is actuated to retract the latch 5 from engagement with the 55 lintel and threshold of the door frame, as hereinbefore described, to allow the door to be opened. The teeth of this segment gear 15 are so disposed relative to the respective pinion 13 that when the door 3 is closed the 60 last tooth of the segment gear has passed

out of engagement with the respective tooth of the pinion 13 whereby the segment is allowed to continue its closing movement independently of the pinion 13, and a spring 44 has its respective ends secured to the arm 70 16 of said segment gear and the adjacent side member of the door frame to actuate said segment gear through its final closing movement. It is during this final movement, which the segment gear 15, makes independent of its pinion 13 that the cam 39 75 actuates the lever 41 to operate the latches 5, and as a result, the latches 5 are operated when the door 3 is at rest in its closed position whereby the latches may be operated 80 without interference by the opening or closing movement of the door.

The teeth of the segment 15 which engages the pinion 13 of the door 2 do not disengage from the pinion when the door 2 85 is closed, and the closing movement of the doors 2 and 3 are so timed relative to each other that the door 2 closes slightly in advance of the door 3 whereby the strip 7 does not interfere with the closing thereof. 90 In order that the doors may always be adjusted properly relative to each other the arms 21 of the rock shaft are adjustable, each arm comprising two members, a lower member which is secured upon the respective end of the rock shaft, and an upper member 44 which is screw threaded upon the free end of the lower member, a nut 45 being threaded upon each lower member and adapted to be clamped against the adjacent end of the respective upper member 95 to secure the same in any position.

Having thus fully described my invention, I claim:

1. In a device of the character described, 105 the combination with a door frame, of a door hingedly mounted therein, a pinion mounted on said door, latches on said door adapted to engage said door frame when the door is shut, a segment gear mounted for pivotal movement on said door frame and adapted to mesh with said pinion, the disposition of said segment being such that when the door is closed the teeth of said gear are out of engagement with said pinion, a cam 110 on said segment gear, a lever mounted on said door and having one end thereof engaging said cam and having the other end thereof in operable relation with said latches whereby said latches are retracted upon the 115 initial opening movement of said segment, and means for operating said segment.

2. In a device of the character described, 120 the combination with a door frame, of a pair of doors hingedly mounted therein, a pinion mounted on each door, latches on one of said doors, an overlapping strip on said latch carrying door adapted to engage the other door to hold it shut, a segment gear mounted 125 for pivotal movement on each of said door 130

frames and adapted to mesh with respective pinions, the disposition of said segment of the latch carrying door being such that when the door has closed the teeth of said segment 5 are out of engagement with said pinion, means in operable relation with said latches and said segment gear of the latch carrying door whereby said latches are retracted upon the initial opening movement of said segment, and means for operating said segments in unison after said segment of the latch carrying door engages its pinion.

3. In a device of the character described, the combination with a standard, a cam 15 member movably mounted on said standard, a lever pivoted on said standard and having a cam surface engageable with said cam, and a spring engaging said standard and cam for normally retaining said cam in its upper position.

4. In a device of the character described, the combination with a door, a standard, a cam member movably mounted on said standard, a lever pivoted on said standard and 25 having a cam surface engageable with said cam, and a spring engaging said standard and said cam for normally retaining said cam in its upper position, and connections between said lever and said door whereby 30 said door is opened when said cam is depressed.

5. In a device of the character described, the combination with a door frame, of a pair of doors hingedly mounted therein, a pinion mounted on each door, a segment gear mounted for pivotal movement on each side of said door frame and adapted to mesh with respective pinions, a rock shaft having an arm on either side of said door frame, each arm having 35 operable connection with its respective segment gear, and a depressible platform having operable connection with said rock shaft whereby said segment gears are operated to open said doors 40 when said platform is depressed.

6. In a device of the character described,

the combination with a door frame, of doors hingedly mounted therein, a pinion mounted on each door, a segment gear mounted for pivotal movement on each side of said door 50 frame and adapted to mesh with respective pinions, a rock shaft having an arm on either side of said door frame, each arm having operable connection with its respective segment gear, a pair of standards, cam members movably mounted on respective standards, a lever pivoted on each standard and having a cam surface engaged with its respective cam, springs for normally retaining said cams in their upper positions, a crank on 60 said rock shaft, connecting rods having respective ends pivotally mounted on said levers and said crank, and a platform mounted on said cams.

7. In a device of the character described, the combination with a door frame, of doors hingedly mounted therein, a pinion mounted on each door, a segment gear mounted for pivotal movement on each side of said door frame and adapted to mesh with respective 70 pinions, a rock shaft having an arm on either side of said door frame, arms on said segment gears, pulleys mounted on respective sides of said door frame, cables trained over respective pulleys and having their respective ends connected to respective arms of said segment gears and arms on said rock shaft, weights having operable connection with each door and adapted to normally retain said doors in closed position, a pair of 75 standards, cam members movably mounted on respective standards, a lever pivoted on each standard and having a cam surface engaged with its respective cam, springs for normally retaining said cams in their upper 80 position, a crank on said rock shaft, connecting rods having respective ends pivotally mounted on said levers and said crank, and a platform mounted on said cams.

In testimony whereof I affix my signature. 85

CHARLES ALBRECHT, JR.
